UNITED STATES PATENT OFFICE

WILL J. ECKER, JR., OF ST. LOUIS, MISSOURI

CARD HOLDER

Application filed July 13, 1931. Serial No. 550,493.

The object of my device is to make a card holder, particularly one of the type to be used for holding visiting cards.

A further object is to make a card holder 5 and to secure the cards to the holder by means of sheets of tissue paper.

A still further object is to perforate the tissue paper holding the cards transversely, so that in the removal of the cards, the tissue 10 paper will be torn along the perforation, thereby permitting the easy removal of the card, as well as the tissue paper and permitting the un torn longer sheet of tissue paper to be used as a scratch pad or memorandum pad.

15 In my device a simple plate of metal or other material is used. A visiting card is placed on the plate. A sheet of tissue paper is placed over the card. On each end of the sheet of tissue paper is formed a stub which 20 is bent around the edge of the plate, and is glued to the plate. A second card is then placed on the sheet of tissue paper. A second sheet of tissue paper of the same shape and size as the first sheet is then superimposed 25 on the second card. The stubs of the second sheet of tissue paper are then glued to the stub of the first sheet of tissue paper. This process is continued until as many cards as desired are placed on the plate and covered 30 with the sheet of tissue paper.

It will be observed that each succeeding sheet of tissue paper, since all the stubs are the same dimension, will be concentrically positioned over the remaining sheets of tissue 35 paper or cards. The lateral edges of the sheets of tissue paper are permitted to extend slightly over the edges of the cards. This is accomplished by making the width of the sheet of tissue paper slightly greater than the width of the card. Since each stub of a sheet 40 of tissue paper must pass over the edge of the original plate, and also over a card and all cards and sheets of tissue paper beneath it, it will not extend as far longitudinally on the 45 back of the plate as did the preceding sheet of tissue paper. By this means, it is obvious that the first sheet of tissue paper is the only one that is secured to the plate, and each succeeding stub is glued to the stub immediately 50 beneath it.

With these and other objects in view, my invention has relation to certain novel features of construction and arrangement of parts, as will be hereinafter more fully described, pointed out in the claims and illustrated in the drawing, in which

55 Fig. 1 is a plan view of the card holder, showing the sheets of tissue paper that may be used as memorandum.

Fig. 2 is a front elevation of the structure 60 shown in Fig. 1.

The upper figure in Fig. 3 is a perspective view of a single sheet of tissue paper, together with the stubs used in my device. The next lower figure is a perspective view of a 65 greeting card.

The lowest figure is a perspective view of the base or plate used in my device. The next higher figure shows a conventional greeting card about to be placed on the base and 70 the middle figure shows a perspective view of a sheet of tissue paper, similar to the upper figure showing it in position to be placed over the card.

75 Numeral 4 designates a plate or base, which may be of metal or other material, rectangular in shape and of the size of the greeting card that is to be detachably secured to it.

Numeral 5 designates the card.

80 Numeral 6 designates a sheet of tissue paper having the transverse perforation 7 and the stubs 8. As previously stated, the width of the sheet of tissue paper 6 is slightly greater than the width of the card 5. The purpose of this is to prevent the soiling 85 of the edges of the cards. The card 5 is placed on the plate or base 4 concentrically. The sheet of tissue paper is placed over the card 5 and the stubs 8 bent around the ends of the card 5 and the plate or base 4. The 90 underside of the stubs 8 by means of the glue 9, are glued to the undersurface of the plate or base 4. The next succeeding card 10 is then concentrically positioned on the sheet of tissue paper 6. The next succeeding 95 sheet of tissue paper is then positioned over the card 10 and the stubs 8 glued to the first stubs 8. In Fig. 2, it is easily seen how each succeeding stub is attached.

100 In operation, the user tears the sheet of

tissue 11 on the perforations 12, and folds back the sheet of tissue 13, as best shown in Fig. 2. Since the card has no attaching means, other than the tissue paper, it may 5 now be removed and the sheet of tissue 13 used as a temporary scratch pad or memorandum pad. The sheet of tissue paper, therefore, performs the dual function of holding the cards together, and on to the 10 plate or base 4, as well as permitting the use as a scratch pad. The sheets of tissue further prevent the soiling of the exposed edges of the cards.

Whenever tissue paper is mentioned in this 15 application, it is to be assumed that other material of similar properties may be substituted.

What I claim is:

1. In combination with a plate, a card, 20 said card positioned on said plate, a sheet of tissue paper positioned above said card, a second card positioned on said sheet of tissue paper, and a second sheet of tissue paper positioned on said second card, said 25 sheets of tissue paper secured to each other, and to said plate, thereby detachably securing said cards between said sheets of tissue paper, and securing said cards detachably to said plate.
2. In combination with a plate, a card positioned thereon, a sheet of tissue paper positioned on said card, stubs formed on said sheet of tissue paper, said sheet of tissue paper secured to said plate by having said stubs 30 bent around said card and said plate, and affixed to the lower base of said plate, said sheet of tissue paper having a transverse perforation formed therein, thereby permitting the facile tearing of said sheet of tissue paper, along the perforation of said sheet of tissue paper, thereby providing a portion of said sheet of tissue paper for a memorandum sheet, a second card positioned on said sheet of tissue paper and a like sheet of tissue 35 paper positioned over said second card the stubs of said second sheet of tissue paper attached to said first sheet of tissue paper, thereby building up a pack of cards and sheets of tissue paper to the number desired, 40 the width of said sheets of tissue paper being slightly greater than the width of said cards.

In testimony whereof I affix my signature.

WILL J. ECKER, JR.
